ARC TUBE SYSTEM

David D. Coffin, Waltham, Mass., assignor to
 Raytheon Manufacturing Company, Newton,
 Mass., a corporation of Delaware

Application July 14, 1939, Serial No. 284,501

15 Claims. (Cl. 175—354)

This invention relates to an arc tube system, and more particularly to such a system in which two controlled arc tubes are connected inversely in order to supply a controlled alternating current load, such as a resistance welding load.

In alternating current systems of this general nature, particularly in the case of resistance welding loads, it is desirable that if one of the arc tubes fails to conduct current upon the application of an igniting impulse to its igniting electrode, the other arc tube shall also be prevented from starting. If this is not done, the current supplied to the load has a substantially direct current component which is usually disadvantageous, especially when undesired magnetic saturation of magnetic elements in the load circuit may result.

An object of this invention is to devise means responsive to the absence of conduction in either tube for deenergizing the firing circuit of the other tube.

The causes which prevent a tube from firing upon the application of an igniting impulse to the igniting electrode are often temporary in character, and therefore it is often desirable to repeat the application of igniting impulses to the tube which fails to fire. Another object of this invention is to devise means for doing this, which means, however, prevents igniting impulses from being supplied to said other tube as long as the first tube fails to fire.

The foregoing and other objects of this invention will be best understood from the following description of an exemplification thereof, reference being had to the accompanying drawing, wherein:

Fig. 1 is a diagrammatic representation of a circuit embodying the present invention; and

Fig. 2 is a curve illustrating the operation of the system shown in Fig. 1.

The embodiment illustrated consists of two arc tubes 1 and 2, preferably of the mercury pool cathode type. These tubes contain mercury pool cathodes 3 and 4, and anodes 5 and 6, respectively, and are provided with igniting electrodes 7 and 8. Although these igniting electrodes may be of any type which initiate an arc on the mercury pool cathode by means of an igniting impulse supplied thereto, they preferably are of the type which consists of a conductor separated from the mercury pool by an insulating layer which preferably consists of glass. More particularly these igniting electrodes may be of the form described and claimed in the copending application of Percy L. Spencer, Serial No. 259,355, filed March 2, 1939,

for an improvement in Arc starting devices. In igniting electrodes of this kind, the glass layer on the igniting electrode conductor is in contact with the surface of the mercury pool, and the arc tends to form at some such point of contact. The upper ends of the electrodes 7 and 8 may be left exposed to the discharge so as to provide discharge paths in parallel with the respective cathodes and igniting electrodes.

Two alternating current lines 9 and 10 are connected to supply a suitable alternating current load which may consist of a transformer 11 having a primary 12, a secondary 13, and a load 14. In the particular system shown, the load 14 may consist of a resistance welding load. The arc tubes 1 and 2 are interposed in one of the conductors 10 in order to control the flow of current to the load. In order to permit alternating current to flow through the tube system, the two tubes are reversely connected by means of the crossed conductors 15 and 16. If the tubes 1 and 2 are conducting, current pulses of one polarity will flow through tube 1, and current pulses of the opposite polarity will flow through tube 2, thus delivering alternating current to the load. If, however, tubes 1 and 2 are non-conducting, the load is deenergized.

Igniting transformers 17 and 18 are provided to supply igniting impulses to the igniting electrodes 7 and 8, respectively. These igniting transformers are provided with secondary windings 19 and 20. The secondary winding 19 is connected between the igniting electrode 7 and the cathode pool 3, while the secondary winding 20 is connected between the igniting electrode 8 and the cathode pool 4. The transformers 17 and 18 are also provided with primary windings 21 and 22 which are supplied with igniting voltage impulses through a control circuit which is energized from a transformer 23 having a primary winding 24 connected directly across the tubes 1 and 2. For this purpose the two ends of the primary winding 24 are connected respectively to the two conductors 15 and 16. The transformer 23 also has a secondary winding 25 which supplies primary windings 21 and 22 with unidirectional impulses through a rectifying bridge. A pair of control contacts 26 are interposed in one of the conductors leading from the secondary winding 25 to the rectifying bridge. These control contacts may be operated from a control pushbutton or from some suitable timing arrangement.

The rectifying bridge comprises four rectifiers 27, 28, 29 and 30, preferably of the copper oxide type. The primary windings 21 and 22 constitute

two outer legs of the bridge, while a conductive connection 31, extending from a point between the rectifiers 27 and 28 to a point between the rectifiers 29 and 30, constitutes the central leg of said bridge. Included in the central leg 31 is a relay armature 32 which normally completes the connection between a pair of contacts 33-33. The armature 32 forms part of a relay 34 which is provided with an operating coil 35. Said operating coil 35 is also in series with the contacts 33-33 in said central leg 31. The polarities of the rectifiers 27-29 are such that rectifiers 27 and 30 allow impulses of one polarity to pass through the primary winding 22, while the rectifiers 28 and 15 29 allow impulses of the opposite polarity to pass through the primary winding 21.

Connected directly across the tubes 1 and 2 is a series circuit consisting of a resistance 36 and a condenser 37. This circuit is to enable 20 the incipient arc spots initiated by the igniting impulses supplied to the igniting electrodes 7 and 8 to progress rapidly into true arc spots irrespective of the nature of the main load. This feature is more fully described and claimed in 25 the copending application of Wilcox P. Overbeck, Serial No. 271,679, filed May 4, 1939, for an improvement in Arc tube systems.

The operation of the system described above can be best understood by referring to the curves 30 shown in Fig. 2. These curves do not purport to show quantitatively the current and voltages involved. However, they do represent in a general qualitative manner the operation of the system. In Fig. 2 the sine wave *a* represents 35 the line voltage which appears across the conductors 9 and 10. The curve *b* represents the load current flowing to the primary winding 12. In the systems which are contemplated, particularly resistance welding systems, the current *b* 40 lags the voltage *a*, and in the particular instance shown, this lag is about 60 degrees. As the current passes through zero, one of the arc tubes 1 or 2 goes out, and normally the other tube starts immediately, delivering smooth alternating current to the load. The curve *c*, which represents the voltage across the tubes 1 and 2, shows that when one of the arc tubes goes out, 45 the voltage across said tubes rises very rapidly to the instantaneous value of the line voltage at that particular moment. The system is so arranged that this voltage impulse is transmitted through the firing circuit so as to ignite the previously idle tube, which thereupon immediately starts conducting current so that the 50 voltage across the tube then drops to the relatively low value of the tube arc drop. This operation takes such a short time that the rise in voltage across the tube lasts for a very short time, and therefore these voltage impulses are 55 represented in curve *c* by vertical lines. Of course it is to be understood that this change does occupy some time interval which, however, it is impractical to illustrate in Fig. 2. It will be seen, therefore, that the voltage across the 60 tubes 1 and 2 supplies voltage impulses at exactly the right moment in order to alternatively fire the tubes 1 and 2 so as to cause the alternating load current *b* to flow smoothly through said tubes. The primary winding 24 which is 65 connected directly across the tubes 1 and 2 has this voltage wave *c* impressed upon it. This same voltage wave *c* is therefore impressed through the secondary winding 25 upon each of the primary windings 21 and 22 connected in 70 series with their respective rectifiers 28 and 29,

and 29 and 30. As described above, voltage impulses of one polarity pass through the primary winding 21, while voltage impulses of the opposite polarity pass through primary winding 22. Thus the impulses of the voltage wave *c* which lie above the zero axis are impressed upon the igniting electrode 7, for example, while those voltage impulses of the wave *c* which lie below the axis are impressed on the other igniting electrode 8, for example. The polarities of the windings on the transformers 17 and 18 are so chosen that the voltage impulses supplied to the igniting electrodes 7 and 8 are primarily positive with respect to the associated cathodes 3 and 4.

When the control contacts 36 are closed, the 15 igniting circuit is energized and the tubes 1 and 2 conduct current substantially as described above. If, however, one of the tubes 1 or 2 fails to become conductive upon an igniting impulse being supplied to its associated igniting electrode 7 or 8, the relay 34 is operated to open the connection between the contacts 33-33. This action may be described in connection with the curves shown in Fig. 2. It will be seen that during normal operation of the system, the voltage which 20 is impressed upon the operating coil 35 of the relay 34 is represented by the complete curve *c*, since both polarities of the curve *c* passed by the rectifying bridge pass through the central conductive connection 31. The only portions of 25 the curve *c* which have any substantial magnitude are the vertical portions. However, these vertical portions, as previously described, are of very short duration, such that they are insufficient to cause the coil 35 to operate the relay 34. If, 30 however, upon the occurrence of an igniting impulse at one of the igniting electrodes, the associated tube does not become conducting, the voltage across the tubes instead of falling to the relatively low value represented by the voltage drop 35 of the tube, continues to follow the line voltage *a*. Therefore, upon the failure of a tube to become 40 conducting, coil 35 is supplied with a considerable voltage which persists throughout the remaining portion of the voltage wave. The relay 34 is so designed that if this voltage persists for a sufficient period of time, the coil 35 will 45 operate the relay 34, thus opening the contacts 33-33. The relay 34 is so designed that this operation may occur at some such point as *p* on 50 the curve *c* in Fig. 2. When the relay 34 is operated and the contacts 33-33 are opened both 55 primary windings 21 and 22 are deenergized, and thereafter no impulses are supplied to the igniting transformers 17 and 18 until the contacts 33-33 are again closed by the armature 32. It 60 will be noted, however, that after the initial occurrence of the voltage impulse to the associated igniting electrode, as represented by the left-hand vertical portion of the curve *c*, voltage 65 is continued to be supplied to the associated igniting transformer until the point *p* is reached, due to the delay in the operation of the relay 34. In many instances, although a tube may fail to 70 ignite, upon the supply of a short igniting impulse thereto, this failure may be due to a temporary cause, and if the igniting voltage persists until said temporary cause is removed, the tube may then ignite properly. The period of delay between the initial application of the igniting 75 voltage and the point *p* affords the associated tube an opportunity to ignite under conditions of this kind. In some instances it may be desirable to provide for a greater increase in flow of current through coil 35 upon the failure of a tube 76

to fire. For this reason the cores of transformers 17 and 18 are so proportioned as to become saturated if the voltages supplied to them are substantially larger than a normal igniting impulse. 5 Thus upon the failure of one of the tubes to fire, the associated transformer 17 or 18 will saturate, lowering its impedance and permitting a greatly increased current to flow through coil 35. This insures a positive and reliable action of 10 the relay 34.

When the relay 34 has been operated at the point p, it persists in its operated or open position for another delay period which may end, for example, at the point k. Thus the igniting 15 transformers are deenergized throughout the period between p and k. This delay period is sufficiently long so that when one of the tubes fails to fire, the igniting transformer associated with the other tube remains deenergized during the succeeding half cycle.

Since the relay 34 closes the contacts 33-33 at the point k, an igniting voltage is reapplied to the tube which has failed to fire during the next period in which the anode of said tube becomes 25 positive. Thus, if the causes which prevented the tube from firing were temporary and existed throughout the previous positive half cycle, the reapplication of an igniting voltage to said tube may permit said tube to fire normally if the tube 30 is then in a condition to do so. If, however, the tube fails to fire, relay 34 is again energized to prevent the other tube from being ignited.

It is usually desirable to provide some adjustment for the periods of delay to which the operation and release of the relay 34 are subjected. 35 Such an adjustment may be afforded, for example, by a tension spring 38, the tension of which may be adjusted by an adjusting screw 39. The adjustment also may be afforded by an adjustable impedance, such as a variable resistance 40 placed across the coil 35. These periods of delay may be subjected to wide variations and still keep the operation of the system within the principles of this invention as described above.

Of course it is to be understood that this 45 invention is not limited to the particular details as described above as many equivalents will suggest themselves to those skilled in the art. For example, some aspects of this invention may be applied to tubes having other types of igniting electrodes. Other types of rectifiers and time delay relays may be utilized. Various other changes and additions may be made to the system as disclosed. It is accordingly desired that the appended claims be given a broad interpretation 50 commensurate with the scope of the invention within the art.

What is claimed is:

1. In combination, a load circuit, circuit means 60 for connecting said load circuit to a source of alternating current, a pair of inversely-connected arc discharge devices interposed in said circuit means for controlling the flow of current to said load circuit, each of said arc discharge devices 65 comprising an anode, a pool type arc cathode, and an igniting electrode adapted to initiate an arc spot on said cathode, an igniting circuit for supplying each of said igniting electrodes with igniting impulses, and means responsive to the 70 appearance of a substantial voltage across said arc discharge devices, upon failure of one arc discharge device to start conducting current, for preventing the other arc discharge device from conducting current.

2. In combination, a load circuit, circuit means

for connecting said load circuit to a source of alternating current, a pair of inversely-connected arc discharge devices interposed in said circuit means for controlling the flow of current to said load circuit, each of said arc discharge devices 5 comprising an anode, a pool type arc cathode, and an igniting electrode adapted to initiate an arc spot on said cathode, an igniting circuit for supplying each of said igniting electrodes with igniting impulses, and means responsive to the 10 appearance of a substantial voltage across said arc discharge devices upon failure of one arc discharge device to start conducting current, for deenergizing the igniting circuit of the other arc discharge device.

3. In combination, a load circuit, circuit means for connecting said load circuit to a source of alternating current, a pair of inversely-connected arc discharge devices interposed in said circuit means for controlling the flow of current to said 20 load circuit, each of said arc discharge devices comprising an anode, a pool type arc cathode, and an igniting electrode adapted to initiate an arc spot on said cathode, an igniting circuit for supplying each of said igniting electrodes with 25 igniting impulses, and means responsive to the appearance of a substantial voltage across said arc discharge devices, upon failure of one arc discharge device to start conducting current during a half cycle, for preventing the other arc 30 discharge device from conducting current.

4. In combination, a load circuit, circuit means for connecting said load circuit to a source of alternating current, a pair of inversely-connected arc discharge devices interposed in said circuit 35 means for controlling the flow of current to said load circuit, each of said arc discharge devices comprising an anode, a pool type arc cathode, and an igniting electrode adapted to initiate an arc spot on said cathode, an igniting circuit for 40 supplying each of said igniting electrodes with igniting impulses, and means responsive to the appearance of a substantial voltage across said arc discharge devices, upon failure of one arc discharge device to start conducting current during 45 a half cycle, for deenergizing the igniting circuits of both arc discharge devices for the succeeding half cycle, and for reenergizing the igniting circuit of said first arc discharge device during the following half cycle.

5. In combination, a load circuit, circuit means for connecting said load circuit to a source of alternating current, a pair of inversely-connected arc discharge devices interposed in said circuit means for controlling the flow of current to said 55 load circuit, each of said arc discharge devices comprising an anode, a pool type arc cathode, and an igniting electrode adapted to initiate an arc spot on said cathode, an igniting circuit for 60 supplying each of said igniting electrodes with igniting impulses, means for energizing said igniting circuits from across said discharge devices, whereby the voltage impulses occurring across said arc discharge devices constitute said igniting impulses, and means responsive to the voltage 65 across said arc discharge devices for deenergizing the igniting circuit of one of said discharge devices when the other of said arc discharge devices fails to fire.

6. In combination, a load circuit having a 70 power factor less than unity, circuit means for connecting said load circuit to a source of alternating current, a pair of inversely-connected arc discharge devices interposed in said circuit means for controlling the flow of current to said load 75

5 nected arc discharge devices interposed in said circuit means for controlling the flow of current to said load circuit, each of said arc discharge devices comprising an anode, a pool type arc cathode, and an igniting electrode adapted to initiate an arc spot on said cathode, an igniting circuit for supplying each of said igniting electrodes with igniting impulses, means for energizing said igniting circuits from across said 10 discharge devices, whereby the voltage impulses occurring across said arc discharge devices constitute said igniting impulses, electro-magnetic means included in each of said igniting circuits and adapted to become saturated upon the occurrence of a voltage impulse of substantially longer duration than a normal igniting impulse, and means responsive to the increased current flow occurring upon said saturation for deenergizing the igniting circuit of one of said arc discharge devices when the other of said arc discharge devices fails to fire.

15 14. In combination, a load circuit, circuit means for connecting said load circuit to a source of alternating current, a pair of inversely-connected gas-filled discharge devices interposed in said circuit means for controlling the flow of current to said load circuit, each of said gas-

filled discharge devices comprising an anode, a cathode, and control means for causing a discharge to be started between said cathode and anode, a control circuit for supplying each of said control means with discharge starting impulses, and means responsive to the appearance of a substantial voltage across said discharge devices upon failure of one discharge device to start conducting current for preventing the other arc discharge device from conducting current.

10 15 15. In combination, a load circuit, circuit means for connecting said load circuit to a source of alternating current, a pair of inversely-connected gas-filled discharge devices interposed in said circuit means for controlling the flow of current to said load circuit, each of said gas-filled discharge devices comprising an anode, a cathode, and control means for causing a discharge to be started between said cathode and anode, a control circuit for supplying each of said control means with discharge starting impulses, and means responsive to the appearance of a substantial voltage across said discharge devices upon failure of one discharge device to start conducting current for deenergizing the control circuit of the other arc discharge device.
